UNITED STATES PATENT OFFICE.

HENRY FAWCETT, OF KIDDERMINSTER, ENGLAND, ASSIGNOR TO J. & J. DOBSON, OF PHILADELPHIA, PENNSYLVANIA.

DESIGN FOR A CARPET.

SPECIFICATION forming part of Design No. 17,961, dated December 20, 1887.

Application filed September 28, 1887. Serial No. 250,974. Term of patent 7 years.

To all whom it may concern:

Be it known that I, HENRY FAWCETT, a subject of the Queen of Great Britain, residing at Kidderminster, England, have invented and produced a certain new and original Design for Carpets, of which the following is a full, clear, and exact description, reference being had to the accompanying drawing, forming a part of this specification.

My invention has relation more particularly to loop and cut pile carpets and to those woven with a border. It is illustrated in the drawing as consisting of a center or body proper of a grouping of grotesque figures symmetrical in form in most part and mostly in contrast with each other, the whole inclosed within a border consisting of two narrow parallel lines with a wide space containing floral figures between

them, and an extra outside row or line of figures mainly of parallel lines at right angles 20 with the main border, and a corner-piece.

I claim—

1. The design for the center or body of a carpet, substantially as shown and described.
2. The design for a carpet-border, substantially as shown and described.
3. The design for a bordered carpet, consisting of the center and border, substantially as shown and described.

In testimony whereof I have hereunto affixed 30 my signature this 24th day of May, A. D. 1887.

HENRY FAWCETT.
